UNITED STATES PATENT OFFICE.

FRANK WATSON, OF PHILADELPHIA, AND ROBERT P. GARSED, OF NORRISTOWN, PENNSYLVANIA.

AUTOMATIC SWITCH FOR RAILROAD-TRACKS.

SPECIFICATION forming part of Letters Patent No. 244,700, dated July 19, 1881.

Application filed August 16, 1880. (No model.)

To all whom it may concern:

Be it known that we, FRANK WATSON, of the city and county of Philadelphia, and State of Pennsylvania, and ROBERT P. GARSED, of 5 Norristown, in the county of Montgomery and State of Pennsylvania, both citizens of the United States, have invented a new and useful Improvement in Apparatus for Operating Railroad-Switches, which improvement is fully 10 set forth in the following specification and accompanying drawings, in which—

Figure 1 is an end elevation of the switch embodying our invention. Fig. 2 is a side elevation thereof.

15 Similar letters of reference indicate corresponding parts in the two figures.

Our invention consists of a circuit-forming rod or lever, in combination with the switch-rails which are connected to automatically- 20 moving devices having a holding-lever, whereby, by the action of an approaching train, the lever may be released by electric action and the switch quickly shifted, as will be herein-after set forth.

25 Referring to the drawings, A A represent the switch-rails, and A' A' the rails of the main line.

B represents an electro-magnet, and B' an armature of catch form above the same, both 30 being connected to a suitable support in a pit, F, near the switch-rails.

G represents an upright lever pivoted to a wall of the pit, having at its lower end a tongue, F', which is adapted to engage with the nose of the armature B', and at its upper 35 end a notch or shoulder for engagement with the end d of a pivoted lever, D, whose support rises from the base of the pit or other proper part thereof, the other end of the lever being weighted or pressed down by means of a suitable spring. To the end d of the lever 40 is attached an arm, E, which, in the present case, is in the form of a slotted segment, through the slot of which is passed a pin or stud, E', projecting from the connecting-bar E'' of the switch-rails A A.

According to the drawings, the switch is shifted to the left and open to the main line, this having been accomplished by means of a 45 removable hand-lever, which is pushed from

the position F'' to the left to the position F''', the end d of the lever being engaged by the top of the lever G.

At the side of one of the main rails, sufficiently removed from the end of the switch, is 55 a head, a, which, supported on an upright rod, a', in a suitable pit, is so located and supported that it may be struck by the forward car-wheel and thereby depressed. The lower end of the rod carries an electric wire, a'', and 60 is adapted to come in contact with the connecting-point a''' of an electric wire, a'''.

It will be seen that when the train approaches and the switch requires shifting, when the head a is depressed, the rod a' is moved against 65 the point a''', and an electric circuit is thereby formed, the result whereof is to attract the armature B', which, being moved, is disengaged from the tongue F' of the lever G. The spring b, which bears against the tongue F' at the 70 lower end of the lever G, forces by sudden impulse said tongue and end to the right sufficient to begin the release of the end d of the lever D, and as said lever G is no longer controlled by the armature B' the weighted lever 75 D, pressing against the top of the lever G, completely clears its end d from the lever G. The stronger spring b', which bears against the lower end of the lever G, opposite to the spring b, resists the movement of the lever G, 80 and when the end d has cleared the top of the latter said spring b forces back the lower end of the lever. When the rod a' is released of pressure and caused to rise by the action of a spring suitably applied the circuit is broken, 85 and the armature is restored to its first position, ready to lock the tongue F'. As soon as the lever D is released it moves and carries with it the arm E, so that the switch-rails are shifted, in the present case, to the right, and 90 thereby communicate with the rails of the main line, thus closing the switch.

When the switch-rails are to be shifted to the left to communicate—say to the side—the handle or key at F'' is inserted in the lever D 95 and moved to the position F'''. The end d of the lever D forces back the top of the lever G until it drops into or against the notch or shoulder of the lever, and thus engages with the same, it being noticed that as the top of the 100

lever is forced back the tongue F', which is in contact with the head of the armature B' and connected to the lever G, yields, owing to its elastic nature, and so permits the movement 5 of said lever G. The hand lever or key is now removed and the train may pass to the siding, and when desired the switch may be operated to the right, as before stated.

The device described is employed for trains 10 passing in one direction of the line, and may be duplicated and adapted for operation of the switch by trains coming in the opposite direction.

Having thus described our invention, what 15 we claim as new, and desire to secure by Letters Patent, is—

1. The switch-rails, in combination with the automatically-shifting lever D, holding-lever G, the armature B', electro-magnet B, and the

circuit-closing rod a', substantially as and for 20 the purpose set forth.

2. The switch-rails, in combination with the circuit-forming rod a', the electro-magnet B, armature B', lever G, springs b b', the shifting-lever D, and connection E, substantially 25 as and for the purpose set forth.

3. The switch-rails, in combination with the shifting-lever D, the holding-lever G, provided with the tongue F', and springs b b', the armature B', electro-magnet B, and circuit-forming 30 devices, substantially as and for the purpose set forth.

FRANK WATSON.
R. P. GARSED.
